UNITED STATES PATENT OFFICE.

JAMES L. TAYLOR, DECEASED, LATE OF POUGHKEEPSIE, NEW YORK; BY EMMA A. TAYLOR AND BESSIE A. MATTHEWS, EXECUTRICES, BOTH OF POUGHKEEPSIE, NEW YORK; SAID JAMES L. TAYLOR, ASSIGNOR TO THE JAMES L. TAYLOR MANUFACTURING COMPANY, OF NEW YORK, N. Y., A CORPORATION OF NEW YORK.

CLAMP.

Original application filed April 7, 1916, Serial No. 89,541. Divided and this application filed September 27, 1919, Serial No. 326,981. Renewed August 10, 1922. Serial No. 581,029.

To all whom it may concern:

Be it known that JAMES L. TAYLOR, deceased, in his lifetime a citizen of the United States, and a resident of Poughkeepsie, in 5 the county of Dutchess and State of New York, did invent certain Improvements in Clamps, of which the following is a specification.

This application is a division of the application of James L. Taylor, deceased, upon 10 a clamp machine, filed April 7, 1916, Serial No. 89,541, allowed April 11, 1919, and relates to the clamp illustrated and described in said allowed application, and used in connection with the clamp machine.

The objects of the invention are to provide an improved powerful and quick-acting clamp; to form the clamp with an extended bed or body portion so as to receive 15 and support short pieces of material in a flat balanced position; for these purposes to use a pair of spaced angle bars; to provide improved stationary and movable jaws; to provide novel means for mounting the 20 movable jaw on the angle bars forming the bed of the clamp; to secure improved adjusting means for the movable jaw in an out-of-the-way position; to provide improved means for adjustably and removably 25 holding forms of various shapes to fit against the side of the work, as in gluing school seats and backs or other curved work; to secure a clamp which is simple and inexpensive in its construction and 30 which will withstand hard usage; to provide a clamp for clamp machines which will ensure that the outer edge of the work is always at the outer end of the clamp, said work projecting inward according to its 35 width; to thus insure that narrow pieces of work are always located in the most accessible position at the outer ends of the clamps, automatically or without special attention; and to obtain other advantages and 40 results as may be brought out in the following description.

Referring to the accompanying drawings, in which like numerals of reference indicate the same parts throughout the several views,

Figure 1 is a perspective view of a clamp 50 constructed in accordance with the invention;

Figure 2 is a side elevation of one of the clamps partly in central longitudinal section as on line 2—2 Fig. 3;

Figure 3 is a top plan view of the clamp 55 showing the face of the clamp which is adapted to receive the work with the form-holding bar removed;

Figure 4 is a transverse vertical sectional 60 view through the same on the line 4—4 Fig. 3;

Figure 5 is an elevation of the free or outer end of the clamp with the adjusting member and its retaining means removed;

Figure 6 is an elevation of the opposite or attached end of the clamp;

Figure 7 is a perspective view of the spanner foot of the clamp;

Figure 8 is a perspective view of the head 70 of the clamp, showing the stationary or fixed jaw;

Figure 9 is a perspective view of the movable jaw;

Figure 10 is a perspective view of a form-carrying plate, and

Figure 11 is a perspective view of a locking member for the clamping nut or handle.

In the specific embodiment of the invention illustrated in the drawings, the numeral 80 1 designates a spanner foot or base casting which is disposed transversely of the clamp and adapted to extend longitudinally of the clamp carrier, as illustrated in the above-mentioned allowed application, having at 85 one end a transverse bearing 2 to receive one of the cross-rods 3 of the clamp carrier and its other end forked as at 4 to receive the next adjacent rod of the clamp machine. The said bearing 2 is a long sleeve adapted 90 to secure a firm bearing upon the rod 3, but the forward forked end 4 is narrower and serves simply to stay the clamp against movement transversely of the rods 3. Intermediate the ends of this spanner foot or 95 base piece 1, and preferably nearer the forked end, an extension 5 projects inward or toward the inside of the endless carrier a

sufficient distance for the purposes next to be described and preferably for the width of the body of the spanner foot, the outer end of said extension 5 being steadied by a brace 6 extending to the sleeve-like bearing, as shown. To the opposite sides of said extension 5 is bolted a pair of angle bars 7, 7 so that two of their flanges lie flatwise against said projection in parallel spaced relation to each other and the other flanges project outwardly apart at the edge of the extension next the sleeve-like bearing 2, and thus substantially midway between the two end bearings of the spanner foot, as shown in Figure 6, forming a supporting surface to receive the work to be clamped. These angle bars project perpendicularly from the spanner foot, outwardly away from the carrier, to the length desired for the clamp, and at their opposite ends are secured to a head 8 to the opposite sides of which they are bolted in the same parallel relation as to the foot or base piece 1.

This head 8 comprises a body against the opposite sides of which the parallel flanges of the angle bars 7, 7 lie, and above the other flanges the head provides a fixed jaw 9 adapted to engage the work and which extends transversely across the body portion and work-supporting flanges of the angle bars. The body portion of the head is apertured below the jaw and between the angle bars 7, 7 so that a screw 10 projects therethrough and is adapted to receive a handled clamping nut 11 at the front of the head, the rear end of the screw being attached to a connecting draw bar 12 which extends backward between the angle bars of the clamp and is secured at its rear end to an adjustable jaw 13 overlying the angle bars transversely thereof and adapted to engage the opposite edge of the work from the fixed jaw 9. This adjustable jaw 13 sits upon the top flanges of the angle bars 7 and has arms 14, 14 extending forwardly downward between and adjacent the parallel flanges of the angle bars and provided at their lower end with ledges 15, 15 to hook therebeneath, all as clearly shown in Figures 2, 3 and 9. Adjacent the jaw proper and at the back of the same, the arms 14, 14 are connected by a cross-piece 16 which serves as a rest for the connecting strip 12, and directly above said rest is the free end of a latch 17 pivoted to the back of the jaw proper and which is normally forced downward by a spring 18 into any one of a longitudinal series of apertures 19 in said strip 12, so as to secure the jaw in fixed relation to said strip. The latch 17 can be released by its handle and set at various points along the length of the connecting strip, according to the width of the work to be clamped, and it will be understood that after it has been so located as near the width of the work as is convenient, the clamp is

tightened against the work by means at the other end, or head, and next to be described.

The body portion of the head 8 is shown recessed at the front, as at 20, Figure 2, to receive the inner end of the tubular or sleeve-like nut 11 provided at its outer end with a suitable handle for turning, and it will be understood that this clamping nut turns loose with respect to the head. To retain it in position with respect to the head a locking member 21, see Figure 11, secured to the head as by a screw 22, provides an arcuate flange 23 which lies outside an annular flange 24 on the nut and adjacent the front of the head, as shown in Figure 2. Preferably this locking member is grooved at its side next the head, as at 25, to fit over a rib 26 to prevent any lateral displacement. The head receives the screw 10 loosely, as at 27, and furthermore is longitudinally grooved at opposite sides of said aperture, as at 28, 28, to enable the connecting strip 12 to be inserted from the front of the head. Preferably wings 29, 29 project from the rear of the lower part of the head to lie against the inner facing sides of the parallel flanges of the angle bars 7, 7 and be riveted thereto, as shown in Figures 2 and 3 more especially, and also said wings have at their upper edges flanges 30 lying beneath the connecting strip 12 and providing a slideway for the same, the upper faces of said flanges being flush with the bottoms of the grooves 28, 28 in the opposite side walls of the aperture 27 of the head, as clearly shown in Figure 8.

It is sometimes necessary to apply on top of the work in the clamp a form to prevent the work from bulging outwardly and to hold it in shape, as for instance in gluing the backs and seats of school furniture and the like. And in providing means for this purpose I aperture the body of the spanner foot 1 or base casting of the clamp, as at 31, adjacent the sleeve-like bearing 2 and pivot therein a bent lever 32 having a socketed forward arm 33 and a rear arm 34 adapted to receive a tension spring 35 connected to the extension 5 of the spanner foot so as to normally throw the socketed arm 33 of the bent lever upward. In said socketed arm is removably inserted a rod 36 adapted to extend the entire length of the clamp and be detachably locked at its forward end to the head 8 when depressed into substantially parallel relation to the clamp against the power of the spring 35. Any suitable means may be employed for so locking the rod, but I have shown it as adapted to be secured by a latch 38 or other suitable means pivoted on the fixed jaw 9. I have shown the pivot 39 of this latch capable of being shifted into various holes 40, Figure 5, to vary the position in which the rod can be clamped and thus accommodate various kinds of work. Upon the rod 36 is a long-

tudinally adjustable block 41 adapted to be clamp without departing from the spirit set wherever desired by a screw 42 and having and scope of the invention, and we do not ing a plate 43 pivoted to its end next the wish to be understood as restricting our work-supporting surface of the clamp in selves except as required by the following:

- 5 any one of a series of holes 44, so as to set claims when construed in the light of the 70
cure further accommodation. This plate is prior art.
provided with holes 45 for wood screws; and Having thus described the invention, what
thus any kind of a form which may be readily shaped out of wood can be secured to the
10 face of said plate 43 and brought against the work in the clamp, as will be understood 75
by those skilled in the art. In case no screw socket and providing a fixed jaw pro-
shaping form is needed for the work being projecting from one of the other sides of said
clamped, the rod 36 is removed from its screw socket transverse thereto, spaced bars
15 socket and laid one side with its block 41 secured at their ends flatwise to said seats on 80
and plate 43. The aperture 31 in the span of the head, means connecting the other ends of
inner foot body, and the bent lever 32 pivot said bars, an adjustable jaw on said bars
ed therein, with its rod 36 are a little to one projecting parallel to the said fixed jaw, and

head for moving said connecting strip longitudinally, a fixed jaw, an adjustable jaw seated on said bars and having between the same a depending portion engaging their under edges and providing a rest for said connecting strip, and means for locking said connecting strip to the adjustable jaw.

6. In a clamp, the combination of spaced bars, means for connecting said bars at one end, a head at the other end of said bars having a body portion adapted to lie between said bars and be secured thereto, said body portion being apertured between the bars and longitudinally thereof, a clamping screw loose in the aperture of the head, a handled nut on said screw at the front of the head, a connecting strip extending rearward from the screw between the bars, and an adjustable jaw adapted to engage said strip.

7. In a clamp, the combination of spaced bars, means for connecting said bars at one end, a head secured to said bars at the other end and having a body portion apertured longitudinally of the bars with grooves in the side walls of said aperture, a clamping screw loose in the aperture of the head, a clamping nut on said screw at the front of the head, a connecting strip extending rearward from the screw through said grooves, and an adjustable jaw engaging said strip.

8. In a clamp, the combination of spaced bars, means for connecting said bars at one end, a head secured to said bars at the other end and having a body portion apertured longitudinally of the bars and provided with rearwardly extending wings having flanges, a clamping screw loose in the aperture of the head, a connecting strip extending rearward from the screw between the bars and upon said flanges of the wings, and an adjustable jaw adapted to engage said connecting strip.

9. In a clamp the combination with a bar, an adjustable jaw thereon, a fixed jaw, and means at one end of said bar for clamping said jaws toward each other, of a rod adapted to lie above work in the clamp, means at the end of said bar away from said jaw clamping means with which said rod may be detachably engaged from the other end of the bar, means carried by said bar and located between said bar and rod intermediate the ends of the latter to hold the work down, and means at the end of the bar next said clamping means for holding that end of said rod down with its work-holding means against the work.

10. In a bar clamp, the combination with a head projecting from the work-receiving face of the clamp, an adjustable jaw, and means at said head for clamping said jaw against the work, of a rod adapted to lie above work in the clamp, means at the end of the clamp away from said head with

which said rod may be detachably engaged from the other end of the clamp, means carried by said bar and located between the work and said rod intermediate the ends of the latter to hold the work down, and means at the said head for holding said rod down with the work-holding means against the work.

11. In a clamp, the combination of a foot and a head projecting from the work-receiving face of the clamp, said foot having a socket, an adjustable jaw, a rod capable of being detachably inserted in said socket from the head end of the clamp to lie above work in the clamp, means between the ends of the rod for engaging said work, and means on the head for releasably engaging the rod to hold the work down.

12. In a bar clamp, the combination with a head and a foot projecting from the work-receiving face of the clamp, and an adjustable jaw between said head and foot, of a lever pivoted to the projecting portion of said foot and having a short socketed arm next the body of the clamp, a tension spring holding the other arm of the lever toward the clamp, a removable rod inserted in said socketed arm of the lever, a pressure plate on said rod, and means on the head for releasably holding the free end of the rod to press said plate toward the work in the clamp, whereby said rod and plate can be removed and the clamp used without them when desired.

13. In a clamp, the combination with a head and foot projecting from the work-receiving face of the clamp, and an adjustable jaw between said head and foot, of a swinging socket pivoted to the projecting portion of said foot, a rod adapted to be removably inserted in said socket and lie above work in the clamp, means between the ends of said rod for engaging said work, means on the head for releasably engaging the rod to hold the work down, and means for swinging said socket to normally hold said rod away from the work.

14. In a clamp, the combination with an adjustable jaw, a fixed jaw, and means extending from one of said jaws to the other for moving said adjustable jaw, of angle bars having two of their flanges substantially parallel and closely adjacent said moving means on opposite sides thereof and extending above and below the same to enclose it, the other two flanges extending outwardly in substantially the same plane to receive work above said moving means and means connecting said angle bars at their opposite ends.

15. In a clamp, the combination of angle bars with two of their flanges substantially parallel and the other two flanges extending outwardly apart in substantially the same plane to receive the work, means connecting

said angle bars at their opposite ends, an adjustable jaw projecting from the plane of said work-receiving flanges and extending between the parallel flanges into engagement 5 with the free edges thereof to resist displacement in clamping, a fixed jaw, and means for clamping the adjustable jaw toward the fixed jaw.

16. In a clamp, the combination of angle 10 bars with two of their flanges substantially parallel and the other two flanges extending outwardly apart in substantially the same plane to receive the work, means connecting said angle bars at their opposite ends, an 15 adjustable jaw engaging both flanges of both bars, a fixed jaw, and means for clamping said jaws together.

17. The combination with a clamp having a work supporting body, and a pressure foot 20 rod, of a pressure foot to engage work on said body, a support for said pressure foot on said rod and adjustable longitudinally thereof, and means for adjustably mounting said pressure foot on said support to accommodate work of different thicknesses. 25

18. The combination with a clamp having a work supporting body, and a pressure foot rod, of a pressure foot to engage work on 30 said body, and a support on said rod adjustable longitudinally thereof for supporting said pressure foot and having a plurality of positive seats to receive said pressure foot to accommodate work of different thicknesses.

19. The combination with a clamp having 35 a work supporting body, and a pressure foot rod, of a support on said rod adjustable longitudinally thereof projecting transversely therefrom and having a series of holes, and a pressure foot having a fastening member adapted to extend through any one of 40 said holes in the pressure foot.

20. In a clamp, the combination of a jaw having an apertured body portion with 45 grooves in the side walls of the aperture, a clamping screw loose in said aperture, a clamping nut on said screw at one side of the jaw, a connecting strip at the other side of the jaw connected to said screw and lying in said grooves, and an adjustable jaw engaging 50 said connecting strip.

21. In a clamp, the combination of an apertured head having bar seats at opposite sides of itself and a fixed jaw at one of its other sides, a screw loose in the aperture of 55 the head, a nut on said screw, a locking member secured to the side of the head opposite said jaw and holding said nut against longitudinal movement, bars secured to said bar seats, an adjustable jaw on said bars, and means connecting said jaw to said screw. 60

22. In a clamp, the combination of angle 65 bars with two of their flanges substantially parallel and the other two flanges extending outwardly apart in substantially the same plane to receive the work, means connecting

said angle bars at their opposite ends, a jaw having one portion between said bars and another portion projecting from between said bars transverse thereto and extending over their said outwardly directed flanges 70 in the same plane and forming therewith an extended seat for the work, a fixed jaw, and means for clamping said jaws together.

23. In a clamp, the combination of angle 75 bars with two of their flanges substantially parallel and the other two flanges extending outwardly apart in substantially the same plane to receive the work, means connecting said angle bars at their opposite ends, a jaw having one portion between said bars and another portion projecting from between said bars transverse thereto and extending over their said outwardly directed flanges 80 in the same plane and forming therewith an extended seat for the work, a fixed jaw, and means between said parallel flanges for clamping said jaws together.

24. In a clamp, the combination of spaced 90 bars, a fixed jaw and a movable jaw on said bars, a connecting strip between said bars, means on the movable jaw for adjustably retaining said connecting strip when it is slid longitudinally into engagement therewith, and means on the fixed jaw for drawing 95 upon said connecting strip.

25. In a clamp, the combination of spaced 100 bars, a fixed jaw and a movable jaw on said bars, a rigid connecting strip between said bars, means on the movable jaw for engaging the connecting strip so as to slide therewith, and means on the fixed jaw for sliding said connecting strip to move the movable jaw away from the work.

26. In a clamp, the combination of a jaw 105 having a seat with a longitudinal groove in the wall thereof, a clamping screw loose in said seat, a handled nut on said screw at the front of the head, a connecting strip extending rearward from said screw and projecting laterally into said groove to resist turning, and a second jaw adapted to be engaged by said strip.

27. In a clamp, the combination of a jaw 115 having a seat with a longitudinal groove in the wall thereof and wings projecting from said seat and providing surfaces forming continuations of side walls of said groove, a clamping screw loose in said seat, a handled nut on said screw at the front of the head, a connecting strip extending rearward 120 from said screw and adapted to engage said groove and wing surfaces to resist turning, and a second jaw adapted to be engaged by said strip.

28. In a clamp, the combination of a jaw 125 having a seat and wings projecting from said seat, a clamping screw loose in said seat, a handled nut on said screw at the front of the head, a connecting strip extending rearward 130 from said screw and engaging said

wings to resist turning, and a second jaw adapted to be engaged by said strip.

29. In a clamp, the combination of a jaw having a seat, and a wing projecting from said seat, a clamping screw loose in said seat, a handled nut on said screw at the front of the head, a connecting strip extending rear-

ward from said screw and engaging said wing to resist turning, and a second jaw adapted to be engaged by said strip.
